TRAVELING WAVE TUBE

Rolf W. Peter, Cranbury, N.J., assignor to Radio Corporation of America, a corporation of Delaware

Application January 4, 1954, Serial No. 401,999

20 Claims. (Cl. 315—3.5)

The present invention relates to improvements in electron tubes and circuits, and particularly to amplifier tubes of the traveling wave type.

In a conventional traveling wave tube an elongated wave-guiding or wave-propagating means, in the form of a section of transmission line with suitable input and output terminals or couplings, is mounted within an evacuated envelope. The terminals are sealed through the envelope or otherwise adapted to be coupled to external transmission lines. The wave-guiding means is designed as a delay line along which electromagnetic waves are guided at a fraction of the velocity of light. The form of delay line most commonly used in traveling wave tubes is a conducting helix, such as a helical metal coil of uniform diameter and pitch. An electron beam is projected by suitable means along, and usually coaxial with, the helix at a beam velocity substantially equal to or slightly higher than the axial wave velocity along the helix. Suitable means is provided for preventing undue spreading of the beam due to space charge effects. In operation of the tube as an amplifier a signal wave traveling along the helix creates electromagnetic fields therealong which interact with the electrons in the beam to produce electron velocity modulation and consequent electron bunching. As the wave and beam travel synchronously along the helix the bunched beam induces electric fields and currents along the helix, causing the amplitude of the wave to increase exponentially. The electron beam gives up direct current energy to the helix, thus producing an amplified signal at the output end of the tube.

In any beam type amplifier tube the signal-to-noise ratio at the output end of the tube is dependent in part upon the amount of noise initially present in the beam. In traveling wave tubes this initial noise is amplified along with the signal by the interaction between the beam and the helix or other wave-guiding means.

The principal object of the present invention is to provide improved means for reducing the overall noise factor of traveling wave amplifier tubes.

Most of the methods of decreasing the noise factor of such tubes that have been used heretofore attempt to eliminate or reduce the amount of noise in the beam prior to modulation thereof by the signal.

In accordance with the present invention, means are provided in a traveling wave tube for preventing, or at least substantially reducing, the amplification of the noise fluctuations present in the beam, at least during a first part of the length of the wave-guiding means where the beam is being modulated by the signal. Farther along the wave-guiding means, after the beam has been modulated to a relatively high level as compared to the noise fluctuations in the beam, amplification of the noise can be tolerated without substantial reduction in signal-to-noise ratio, or increase in overall noise factor, of the tube.

It is known that the noise fluctuations of an electron beam under space-charge-limited conditions leaving the potential minimum originate essentially as velocity fluctua-

2

tions only. These fluctuations produce noise standing waves with maxima and minima of current-density and velocity fluctuations alternately spaced along the beam. When such a beam is used in a conventional traveling wave tube the interaction between the beam noise and the wave-guiding means is greatest only in short periodically-recurring regions therealong where the current density fluctuations of the beam noise are at maximum amplitude. However, the signal wave traveling along the wave-guiding means interacts with the beam continuously therealong. According to the present invention, the coupling between the beam and the wave-guiding means in a traveling wave tube is varied or changed periodically along the length thereof in such manner that the coupling is high in regions of minimum noise current fluctuations (where a minimum of amplification of noise will occur) and either low or zero in regions of maximum noise current fluctuations, at the center frequency of the desired operating bandwidth of the tube. As a result, the beam is modulated by the signal wave in the regions of high coupling with a minimum amplification of the noise of signal frequency in the beam.

The coupling between the beam and the wave-guiding means can be varied or changed, in accordance with the invention, in several ways. The distance or spacing between the beam and the wave-guiding means can be periodically varied along the beam path, by varying the transverse dimensions of either the beam or wave-guiding means while keeping the transverse dimensions of the other constant. The coupling may be changed in a discontinuous manner, as by subjecting the beam to modulating electric fields only in discrete regions periodically located along the beam path at noise current minima and shielding the beam from the modulating fields in other regions. The coupling may also be varied by using as the wave-guiding means a pair of coupled delay lines, such as coaxial helices. The wave energy fed into one helix is transferred periodically between the helices as the wave travels therealong, and the coupling between the beam and the wave varies therealong with the radio-frequency potential on the nearest helix.

When it is desired to vary the coupling by varying the beam diameter, a hollow wave-guiding means, such as a wire helix or a baffle-loaded, waveguide is preferred. The variation in beam diameter may be produced by focusing the beam by means of either an axial magnetic field of suitable intensity or a suitable periodical electrostatic lens structure. When the dimensions of the wave-guiding means are to be varied, the latter may be a wire helix, with or without supplementary coupling means, a "disc-on-rod" structure with a hollow surrounding beam, or a baffle-loaded wave-guide, for examples.

Actually, an electron beam has a random velocity distribution at the cathode which results in random noise velocity modulation of the electrons in the beam over a very broad range of frequencies. However, it is only necessary to avoid appreciable amplification of noise in the frequency range for which the tube is designed to operate. The points of maxima and minima of the noise or plasma standing wave can be calculated from known formulas, or located by probing along a beam in an experimental tube with a resonant cavity tuned to the center frequency of the desired bandwidth. In designing a traveling wave tube with variable coupling it is preferable to locate the input end of the helix, or other wave-guiding means, at or near the first noise current minimum from the cathode. As pointed out above, the coupling may be varied along the entire length of the tube but is preferably varied only for a distance sufficient to produce substantial modulation of the beam by the signal to establish a sufficiently high signal-to-noise ratio.

It has been previously proposed that the coupling between the beam and the helix in a traveling wave amplifier tube be made lower at the input end than at the output end, to reduce amplification of noise during the initial modulation of the beam. However, no attempt has been made heretofore to vary the coupling periodically, with the coupling low in regions of high noise current and high in regions of low noise current.

In the drawing:

Fig. 1 is a schematic view of the standing wave pattern along an electron beam;

Fig. 2 is a graph showing schematically how the coupling between the beam and the wave-guiding means in a traveling wave tube may be varied along the beam path in accordance with the invention;

Fig. 3 is a longitudinal sectional view of a traveling wave tube embodying the present invention;

Fig. 4 is a similar view of another embodiment of the invention;

Fig. 5 is a similar view of still another embodiment;

Fig. 6 is a transverse section taken on the line 6—6 of Fig. 5;

Fig. 7 is a fragmentary view of a modification of Fig. 5;

Fig. 8 is a transverse sectional view taken on the line 8—8 of Fig. 7;

Fig. 9 is a longitudinal sectional view of a traveling wave tube of the plural-cavity type embodying the invention; and

Fig. 10 is a fragmentary view of a further modification of Fig. 5.

Referring now to the drawings in detail, Fig. 1 follows Hahn and Ramo (S. Ramo, Phys. Rev., vol. 56, p. 276, 1939) and illustrates a stationary space-charge standing wave pattern produced by an alternating perturbation on a moving electron beam of uniform diameter with high and low alternating current density regions as indicated. The transverse planes at which the alternating current density maxima and minima occur are indicated by the letters *a*, *b*, *c*, *d*, *e*, etc. The distance between successive maxima, or successive minima, is half of a plasma wavelength, λ_p , that is, the wavelength of the space-charge standing wave pattern. Fig. 1 is general, and applies to a standing pattern produced either by velocity modulation of the beam by a signal of given frequency or by noise velocity fluctuations of a given frequency originating at the cathode. In the case of beam noise, the noise velocity fluctuation, or alternating current velocity, is a maximum and the noise current fluctuation, or alternating current density, is a minimum, at the origin of the velocity fluctuation, that is, at or near the cathode surface. The plasma wavelength is a function of beam velocity, among other variables, and hence does not become uniform along the beam path until after the beam has been accelerated by the gun electrodes to the operating velocity. Hence, the point *a* in Fig. 1 represents some low density region at or beyond the final accelerating electrode of the gun.

Fig. 2 shows schematically how the coupling or interaction between the beam and the helix, for example, in a traveling wave tube may be periodically varied, along at least a part of the length of the helix, in accordance with the invention, to provide high coupling in regions of low noise current, for modulation of the beam by the signal on the helix, and low coupling in regions of high noise current to avoid amplification of the noise initially present in the beam. The upper curve represents the noise current standing wave, corresponding to the solid curve in Fig. 1, but on a different scale, and the lower curve represent the variation in coupling. The wavelength, λ_c , of the coupling wave is approximately equal to $\lambda_p/2$. The phase angle between the periodicities of λ_c and λ_p should be kept as low as possible. The coupling variation could be continued throughout the length of the helix, but this would result in an un-

necessary loss in gain or amplification of signal. Therefore, it is preferable to terminate the coupling reductions as soon as the signal-to-noise ratio in the beam is sufficiently high that amplification of the noise can be tolerated without increase in the overall noise factor of the tube.

Fig. 3 shows the invention embodied in a helix-type traveling wave tube. The tube comprises essentially an elongated dielectric envelope 1 containing a helix 3 of uniform diameter and pitch, an electron gun 5 adapted to project an electron beam B through the helix 3, and external electromagnets 7, 8 and 9, or other suitable means, for establishing an axial focusing magnetic field of suitable intensity along the beam path. The gun 5 is designed to produce a beam that is initially divergent at the cathode in which case the axial magnetic field deflects the electrons moving in paths at an angle thereto and causes the beam to be periodically focused and defocused. Thus, the beam envelope is scalloped, with successive maximum and minimum diameters, as shown in Fig. 3. The first electromagnet 7 is designed to produce a strong magnetic field along the gun 5 and a predetermined part of the helix 3. Due to the variation in beam voltage within the gun 5 the distance between maximum diameter regions varies up to the helix. Within the helix this distance is uniform for a given magnetic field. This focusing and defocusing of the beam causes the distance or spacing between the beam and the surrounding helix 3 to be periodically varied along the helix, resulting in variable coupling therewith. In accordance with the invention, the strength of the magnetic field of electromagnet 7 is chosen relative to the other parameters to make the focus or coupling wavelength, λ_c , equal to half the noise or plasma wavelength, λ_p , of the beam for the center frequency of the amplification bandwidth of the tube, and to cause the minimum diameter regions of the beam to coincide with the noise current maxima along the beam. Moreover, the input end of the helix is preferably located substantially at a noise current minimum, or coupling maximum. The electromagnet 7 extends along the beam for at least two noise current minima, or beam diameter maxima, as shown in Fig. 3. Beyond electromagnet 7 is a short transition electromagnet 8 adapted to produce a magnetic field somewhat weaker than that of electromagnet 7. From electromagnet 8 to the end of the beam path is an electromagnet 9 adapted to produce a relatively weak magnetic field. In the transition electromagnet 8 the focusing force is reduced, which results in a larger minimum beam diameter. In the electromagnet 9 where the focusing field is weaker, so that the beam diameter stays large, the coupling is high for amplification of the signal throughout the major portion of the helix. The transition electromagnet 8 can be omitted.

The divergent beam gun structure 5 is essentially the same as the low-noise gun disclosed and claimed in my copending application Serial No. 385,064, filed October 9, 1953, now Patent No. 2,909,704, granted October 20, 1959, assigned to the same assignee as the present application, and comprises a cathode 11, a concave focusing ring 13 having its inner edge located behind the emissive surface of the cathode, a first accelerating electrode 15, and one or more other accelerating electrodes 17. The last accelerating electrode 17 is connected for direct currents to the helix 3 by a coil 19 and a coupling sleeve 21. By using the low-noise gun shown in Fig. 3, the beam noise is reduced in addition to the advantages of the periodical coupling in preventing amplification of the beam noise. However, the periodical coupling can be used with other gun structures.

The coupling sleeve 21 and a similar coupling sleeve 23 at the output end of the helix 3 are connected to the helix by helix extensions 3' and 3'' which are coupled respectively to external input and output waveguides 25 and 27. Each of the electromagnets 7 and 9 are made

in two sections to provide room for the wave guides. The beam is collected by a collector 29. The helix 3 and gun 5 may be supported within the envelope in any conventional manner.

The variation in beam diameter can be applied to any tube having a hollow wave-guiding means through which the beam is projected. Fig. 4 shows the invention applied to a baffle-loaded waveguide type which is suitable for use with electro-static focusing, instead of magnetic focusing. In this tube the delay line comprises a series of centrally-apertured metal discs 31 connected together for radio frequency currents at their outer edges by metal rings 33. The discs and rings are arranged in groups, of four discs in each ring as shown, for example, separated by electrical insulation discs 35, to permit the application of a different direct-current potential to each group for electrostatic focusing purposes. As indicated on the drawing, alternate groups are maintained at a given potential, V_0 , and the other alternate groups are maintained at a different potential, $V_0 \pm \Delta V$. Any conventional electron gun 5 which will project a suitable beam along the axis into the waveguide may be used. The small and large diameter regions of the beam are correlated with the noise current maxima and minima, respectively, as in Fig. 3. Preferably, the beam focusing is produced by only about two groups of discs, beyond which the metal discs 31 are maintained at the same direct-current potential. Suitable means, such as a shielded electromagnet may be provided to prevent the beam from spreading beyond the two groups. Instead of an electro-magnet, the remaining metal discs 31 could be separated into insulated groups of smaller axial length to provide electrostatic focusing with shorter focal length and smaller variations in beam diameter.

In Figure 4 the rings 33 are sealed to the insulation discs 35 and serve as part of the vacuum envelope of the tube. The envelope is completed by a dielectric gun portion 37 sealed to the first disc 31 by a Kovar ring 38, and a collector 39 sealed to the last disc 31 by a dielectric ring 41 and intermediate Kovar rings 43 and 45. The input and output couplings of the tube may be waveguides 47 and 49 coupled to the input and output ends of the tube by dielectric windows 51 and 53.

In the embodiment shown in Figure 5 an electron gun 5 projects a substantially uniform diameter electron beam along the axis of a helix 55 of variable diameter, whereby the spacing between the beam and the helix is varied, along at least a part of the length of the helix. The ends of the helix 55 are coupled to external input and output waveguides or resonators in a manner similar to that shown in Figure 33. The helix 55 is preferably constructed with a small diameter at the input end and periodically changing diameter for two maximum diameter portions as shown. Each of the minimum portions are located substantially at a noise current minimum of the noise standing wavelength along the beam for the center frequency of the operating bandwidth of the tube, to obtain maximum coupling at those portions. Beyond the second maximum diameter portion the diameter is kept constant at a relatively small diameter throughout the remaining portion of the helix, for high coupling to the beam.

The helix 55 may be supported by means of three longitudinally extending insulating strips 57, of ceramic, for example, which are scalloped to fit the outer envelope of the helix 55. The three strips 57 may be maintained circumferentially in position by ceramic rings 59 having notches for the strips 57, as shown clearly in Figure 6. The gun 5 may be any conventional gun which will provide a parallel-flow beam having a diameter somewhat less than the minimum diameter of the helix 55. The gun shown in Figure 3 may be used if the focusing and accelerating electrodes are maintained at potentials in producing parallel-flow rather than divergent flow. An electromagnet may be provided along the length of the

beam path for establishing an axial magnetic field therealong to keep the beam from spreading due to space charge effects.

Figure 7 and 8 show a modification of Figure 5 in which use is made of the helix 61 of uniform diameter and pitch provided with coupling rings 63 each attached to one turn of the helix by means of a tab 64 and having its central aperture coaxial with the beam path. This type of coupling between the beam and the helix is disclosed and claimed in a copending application of W. J. Dodds, Serial No. 305,797, filed August 22, 1952, now Patent No. 2,802,135, granted August 6, 1957, assigned to the same assignee as the present application. In accordance with the present invention, the central apertures 65 in the coupling rings 63 are varied in diameter periodically along at least a predetermined portion of the helix 61, in a manner similar to the variation in diameter of the helix itself in Figure 5, to vary the coupling between the beam and the helix. The apertures in the coupling rings located at or near noise current maxima would have a large diameter and the aperture in coupling rings located near noise current minima would have a small diameter. The helix 61 and associated coupling rings 63 would be substituted in the tube shown in Figure 5 in place of the variable-diameter helix and its supporting ceramic members, the remainder of the tube being the same as that of Figure 5.

In the embodiment of the invention shown in Figure 9 the coupling between the beam and the modulating electric fields is discontinuous, in that a beam is projected by a gun 5 through a series of cavity resonators 67 to a collector 69. Each of the resonators 67 is coupled by a coaxial line 71 to a delay line 73 along which a traveling wave is adapted to be propagated, whereby modulating electric fields are set up along the beam path across gaps 75 in the resonators 67. Each of the spaces between the resonators 67 is shielded by a tubular shield 77 surrounding the beam path and connected to the resonators 67. Each of the gaps 75 of the resonators 67 is located substantially at a noise current minimum of the noise standing wave in the beam for the center frequency of the operating range of the tube. Thus the noise current maxima in the beam occur within the shields 77 and midway between the electric field gaps 75. Therefore, the beam is coupled to the signal line 73 substantially only in a region of minimum noise current, thereby avoiding the amplification of noise during modulation of the beam. The resonators 67 and shields 77 serve as a part of the vacuum envelope in a manner similar to the tube of Figure 4. The gun 5 and collector 69 are associated with the other structure as in Figure 4. One or more electromagnets may be provided to prevent the beam from spreading.

The helix structure shown in Figure 10 may be used in place of that shown in Figure 5. This structure comprises an inner helix 78 of uniform diameter and pitch, positioned closely adjacent the inner surface of the dielectric envelope 1, and an outer helix 79 closely surrounding the envelope 1 and inductively coupled through the dielectric envelope to the inner helix 78. The outer helix 79 has constant diameter and pitch over a predetermined distance A such that the axial wave velocity along the outer helix 79 is substantially the same as that along the inner helix 78. Beyond the portion A the outer helix 79 is gradually increased in pitch toward the output end of the tube. If desired, the outer helix 79 may be terminated a short distance beyond the portion A. The input signal is coupled to the inner helix 78 by means of a coupling ring 81 and helix extension 78' which is adapted to be coupled to an exterior input waveguide in a manner similar to that shown in Figure 3, except that in Figure 10 the sleeve is located beyond the end of the helix.

In operation of the tube of Figure 10, an input traveling wave is introduced to the inner helix by means

of the coupling extension 78'. As is well known in the art, when a traveling wave is introduced into one of two closely coupled helices having substantially the same axial wave velocity the wave energy fed into one helix is transferred periodically between the two helices as the wave travels therealong. Thus, the radio frequency potential along either helix is periodical. In Figure 10 the beam projected through the inner helix 78 couples primarily to that helix, with little coupling to the outer helix 79. Therefore, the effective coupling between the beam and the two helices varies substantially as the instantaneous potential along the inner helix 78. This results in a periodically-variable coupling between the beam and the traveling wave. The two helices are designed so that, along the portion A, the periodicity or wavelength, λ_t , of the transfer of wave energy from one helix to the other, or in other words, the wavelength of the radio frequency standing wave along the inner helix 78, is equal to one-half the noise or plasma wavelength of the noise standing wave in the beam for the center frequency of the desired operating frequency range of the tube. The value of λ_t for a given pair of coupled lines can be determined experimentally by introducing a wave at the end of one line and probing along either line with a standing wave detector to determine the points of maximum potential. The value of λ_t can also be computed by using the formulas set forth by L. A. Pipes in a paper entitled "The Matrix Theory of Four-Terminal Networks," Phil. Mag. (30), 7th Series, p. 370, 1940. Furthermore, since the energy is fed initially to the inner helix 78, a potential or coupling maximum occurs at the input end thereof, and hence, the input end should be located substantially at a noise current minimum of the noise standing wave. The portion A includes at least two noise current minima. Beyond the portion A, the increase in the pitch of the outer helix 79 reduces the coupling between the two helices and causes the radio frequency potential and coupling along the inner helix 78 to remain high throughout the remainder of the length of the tube. It will be understood that the energy may be fed initially to the outer helix 79 instead of the inner helix 78, in which case the input end of the helix 79 would be located substantially at a noise current maximum. This arrangement has the advantage that the input and output transmission lines can be easily connected directly to the outer helix.

What is claimed is:

1. A traveling wave tube adapted to operate over a predetermined frequency range comprising an elongated wave-guiding structure adapted to propagate a traveling wave therealong at a given axial velocity which is a fraction of the velocity of light, signal input means directly connected to one end of said structure, signal output means directly connected to the other end of said structure, and means for producing along said structure an electron beam having for any given frequency a noise standing wave with noise current maxima and minima alternately located therealong and having a beam velocity substantially equal to or slightly higher than said axial wave velocity for interaction with said traveling wave, the coupling between said structure and said beam being substantially higher in regions of noise current minima than in regions of noise current maxima of the noise standing wave for the center frequency of said operating range, at least for the first two noise current minima and the intermediate noise current maximum of said wave along said structure, whereby during operation said beam can be modulated by a signal wave traveling along said structure in the regions of higher coupling with a minimum of amplification of said noise standing wave.

2. A traveling wave tube as in claim 1, wherein the differences in coupling result from said structure and said beam being spaced farther apart in the region of

said noise current minima than in the region of said noise current maxima.

3. A traveling wave tube as in claim 2, wherein the transverse dimensions of said structure are substantially constant, and the spacing between said structure and said beam is varied by varying the transverse dimensions of said beam along said structure.

4. A traveling wave tube as in claim 2, wherein the transverse dimensions of said beam are substantially constant, and the spacing between said structure and said beam is varied by varying the transverse dimensions of said structure.

5. A traveling wave tube as in claim 1, wherein said wave-guiding structure comprises means for subjecting said beam to axial radio frequency modulating electric fields only in relatively short discrete regions located along the beam path at or near said noise current minima, and means for shielding said beam in other regions.

6. A traveling wave tube as in claim 1, wherein said wave-guiding structure comprises a series of cavity resonators each coupled to said beam at or near a noise current minimum, conductive shields surrounding the beam path between said resonators, and a delay line coupled to said cavity resonators.

7. A traveling wave tube as in claim 1, wherein said wave-guiding structure comprises a first delay line extending along and coupled to said beam and a second delay line closely coupled to said first delay line and having an axial wave velocity substantially equal to that of said first delay line for at least a half plasma wavelength.

8. A traveling wave tube as in claim 7, wherein said first delay line is a first wire helix, having a given circumference-to-pitch ratio, surrounding said beam, and said second delay line is a second wire helix, having substantially the same circumference-to-pitch ratio at the input end thereof, surrounding said first helix.

9. A traveling wave tube as in claim 8, wherein the pitch of said second helix increases gradually from said input end.

10. A traveling wave tube as in claim 1, comprising means for preventing substantial spreading of said beam due to space charge effects.

11. A traveling wave tube comprising an elongated helix adapted to propagate a traveling wave therealong at a given axial wave velocity which is a fraction of the velocity of light, signal input means directly connected to one end of said helix, signal output means directly connected to the other end of said helix, and means for projecting a beam of electrons along said helix and having a beam velocity substantially equal to or slightly higher than said axial wave velocity for interaction with said traveling wave, the coupling between said helix and said beam being periodically varied along a predetermined portion of the length of said helix with at least two maximum coupling regions and at least one intermediate minimum coupling region near the input of said helix, the first of said maximum coupling regions being located substantially at the input end of said helix.

12. A traveling wave tube as in claim 11, wherein said coupling variation results from said helix and said beam being spaced substantially farther apart in said minimum coupling region than in said maximum coupling regions.

13. A traveling wave tube as in claim 11, wherein the transverse dimensions of said helix are substantially constant and the transverse dimensions of said beam are varied along said portion.

14. A traveling wave tube as in claim 11, wherein the transverse dimensions of said beam are substantially constant and the transverse dimensions of said helix are varied along said portion.

15. A traveling wave tube as in claim 11, wherein the transverse dimensions of said beam and said helix are substantially constant, and the coupling between said beam and said helix is varied by means of coupling rings.

of variable diameter periodically distributed along said helix and surrounding said beam.

16. A traveling wave tube as in claim 11, wherein said beam is projecting along the central axis of said helix, and said coupling variation is produced by a second helix, surrounding and coupled to said first-named helix, and having an axial wave velocity along said portion substantially equal to that of said first-named helix.

17. A traveling wave tube as in claim 16, wherein the pitch of said second helix is such that the wave velocity therealong increases gradually from said portion.

18. A traveling wave tube as in claim 3, wherein said structure is an elongated helix of constant diameter and pitch and wherein the transverse dimensions of said beam are varied by means for producing an axial magnetic

10

15

field along said helix and means for causing electrons of said electron beam to enter said magnetic field at an angle thereto.

19. A traveling wave tube as in claim 1, wherein the first of said first two noise current minima occurs substantially at the input end of said wave-guiding structure.

20. A traveling wave tube as in claim 11, wherein the first of said maximum coupling regions is located substantially at the input end of said helix.
